W. B. Gleason,

Crimping Leather,

No 84,743.

Patented Dec. 8, 1868.

United States Patent Office.

WILLIAM B. GLEASON, OF CONNEAUTVILLE, PENNSYLVANIA.

Letters Patent No. 84,743, dated December 8, 1868.

IMPROVED BOOT-CRIMPER.

The Schedule referred to in these Letters Patent and making part of the same.

To all whom it may concern:

Be it known that I, WILLIAM B. GLEASON, of the borough of Conneautville, in the county of Crawford, and State of Pennsylvania, have invented a new and useful Machine for Crimping Boots; and I do hereby declare the following to be a full and exact description of the construction and operation of the same, reference being had to the accompanying drawings, and the letters of reference marked thereon, the same being a part of this specification, in which—

Figure 1 is a perspective view;

Figure 2 is an inside view of one of the uprights or ends;

Figure 3 is a top view of the jaws;

Figures 4, 5, and 6 are sectional views of the crimping-board; and

Figure 7 is a top view of one of the uprights.

The way in which I construct a machine is as follows:

A wooden or iron frame-work, consisting of two uprights, F F, and a cross-piece, J, is first constructed.

On the inside of the uprights is cut a groove, T T, with the guides G G G G.

In these grooves fit the cogged rack-slides C and D, which are propelled by the gears B B on the shaft A, with the lever E.

These are hung on the uprights, F F, by the brackets H H.

This portion of my invention, together with the crimping-board L, I denominate "the brake."

Tenoned into the cross-piece J, are the two jaws, I I. These fit loosely in the mortises, so they can be spread apart at the top.

Fig. 3 shows this part of my invention more perfectly, being a top view of the jaws, in which I I are the jaws, through which passes a bolt, K, on the end of which is a thumb-screw, U, which is used in giving more or less tension to the spring V.

By means of this contrivance the jaws are made adjustable, so that when the machine is being operated they will adjust themselves to the thickness of the leather.

The adjustability can be varied by the thumb-screw U.

These jaws may be made of wood or metal, as may be desired.

Fig. 2 shows an inside view of one of the uprights, F, together with that portion of the brake which is thereto attached, i. e., the half gear B, the rack D, and the guides G G.

Fig. 7 is a top view of this portion of my invention.

On the lower end of the rack D, in fig. 2, will be seen a mortise, Y, and a similar mortise will also be noticed at the upper end of the rack C, in fig. 1.

In these mortises fit the ends of the crimping-board L, seen in fig. 1, which, as has been before mentioned, forms a part of the brake.

Figs. 4, 5, and 6 are sectional views of this portion of my invention.

The crimping-board L is made of any absorbing-material of sufficient strength.

Projecting from the crimping-board L are the arms Z¹, Z², Z³, Z⁴, and Z⁵, (the latter, Z⁵, is not seen, but its place is indicated by the position of the letter in fig. 1,) which act as guides to the grab-bars S S and M.

These bars are triangular in shape, as will be seen in the sectional views, figs. 4, 5, and 6, and they are also ribbed or notched.

Fitting over these are the spring-grabs O O O O and Q, which are V-shaped, and are notched or ribbed, so as to correspond with the grab-bars, thereby being capable of gripping the leather firmly.

a a a a are strips of leather, which are designed to show the action of the grabs.

Passing through the grab-bars S S, at the points marked X X, are thumb-screws P P, which have their bearings on the crimping-board L.

By means of these screws the grab-bars S S can be raised, and the leather be stretched, to suit the operator.

The grabs marked O can be increased in number, to suit the operator.

The grab Q and grab-bar or block M are held between the arms Z² and Z³ by the bevel-guides on the arms and grooves in the ends of the grab-block M.

This grab is operated by a crank-screw, R, which is fastened to the grab-block M.

This screw has its bearing on the top of the cross-piece b, which is fastened to the top of the arms Z² and Z³ by a mortise and tenon.

This grab is used in stretching that part of the boot known as the shank, and, as the wrinkles caused by braking and crimping come in this part of the boot-top or upper, more care is needed than at any other point; and on account of the thinness of the grab-block M, the leather is drawn close to the crimping-board L, and by working the lever carefully, with the crimping-board L in the adjustable jaws I I, the wrinkles are obviated.

In fig. 5, which is a sectional view of this portion of my invention, it will be seen that the crimping-board L is wedge-shaped. This, in connection with the adjustable jaws I I, insures, I claim, a more perfect brake than has heretofore been in use.

The manner in which my machine is operated is as follows:

The boot-upper or front which the operator desires to crimp is first moistened, as usual, and is then placed in position on the face of the jaws.

The lever E is then brought down, and thus, by means of the cogged gears B B and the rack-slides C and D, the crimping-board L is forced down between the jaws, drawing the boot-front with it. This brakes the boot.

The grab Q is then attached to the corners of the shank, and is then screwed up as tight as may be deemed necessary.

The lever is then raised, and the thumb-screw U

may be tightened a little; then the lever is again forced down.

The grabs O O O O are then attached, and the thumb-screws P P are applied. This draws the foot and leg of the boot-front to position.

The lever may be then worked up and down a few times, and all the grabs tightened.

The boot is then crimped, when the crimping-board L and its immediate attachments are removed, and the leather allowed to dry on the board.

A new crimping-board is attached to the racks C and D, and the work goes on the same as described.

Herein will be noticed one of the objects of my invention, viz, obviating the necessity of first braking the boot-front, and then removing it from the brake, and drawing and tacking it on to the crimping-board by hand, as has heretofore been done.

Each machine is supplied with as many crimping-boards (thereby meaning the board L, bars S S, block M, and grabs O O O O and Q) as the purchaser may desire.

What I claim as my invention, and desire to secure by Letters Patent of the United States, is as follows, to wit:

1. The grab-bars S S, spring-block M, the movable spring-grabs O O O O, all constructed substantially as set forth.
2. The crimping-board L, combined with the grab-bars S S, spring-block M, and movable spring-grabs O O O O, for the purposes as set forth.

WILLIAM B. GLEASON.

Witnesses:

MANUEL LANDON,
JNO. K. HALLOCK.
